UNITED STATES PATENT OFFICE.

PATRICK W. SHIELDS, OF PITTSBURGH, PENNSYLVANIA.

BOTTLING-MACHINE.

1,195,515.

Specification of Letters Patent. Patented Aug. 22, 1916.

Application filed March 3, 1906. Serial No. 304,006.

To all whom it may concern:

Be it known that I, PATRICK W. SHIELDS, a citizen of the United States, residing at Pittsburgh, in the county of Allegheny and State of Pennsylvania, have invented a new and useful Improvement in Bottling-Machines, of which improvement the following is a specification.

My invention relates to machines for filling bottles with liquids, and is particularly applicable for use with aerated waters.

The object of the invention is to provide a simple, rapid, efficient and automatic machine of this character, in which the filling operation is dependent upon the presence of a bottle on its support, while the amount of liquid charged into the bottle can be accurately controlled.

My machine provides means for filling bottles of about the same cubical contents with the same amount of water and provides an air reservoir whose cubical contents can be varied, so that the air forced out of the bottles can be compressed to a predetermined limit within this chamber, and thereby check the flow of filling liquid into said chamber. By means of the adjustment of the contents of this chamber, bottles of a larger or smaller capacity can be filled on the same machine. The machine also provides for continuous operation, progressively filling a plurality of bottles.

In the drawings, in which I show one form of machine embodying my invention, Figure 1 is a side elevation of my improved machine; Fig. 2 is a rear elevation of the same; Fig. 3 is a plan view; Fig. 4 is a detail sectional view showing my preferred form of air chamber; Fig. 5 is a cross section on the line V—V of Fig. 4; Fig. 6 is a view similar to Fig. 4, showing a different adjustment of the air chamber; and Figs. 7, 7^a and 7^b are views of the cams for operating the three bottle-filling devices shown.

In the drawings, I show a base frame comprising end standards 2, 2, supporting a table 3, and a lower table 4. Mounted on the table 3 are cylindrical end standards 5, carrying at their upper ends a cross frame 6, having bosses 7 with tapped openings. I show three distinct bottling mechanisms mounted on the frame and will describe one of them, the same numerals being applied to the same parts of the various bottling mechanisms. These bottling mechanisms are

fixed against lateral or sidewise movement and are arranged in longitudinal alignment, so that the moving parts thereof may be actuated from a common shaft.

The table 3 has upwardly and downwardly projecting bosses 8 and 9, which serve as guides for the reciprocating rods 10, arranged in pairs for each mechanism, and extending therethrough. The upper and lower ends of these rods are connected by the cross heads 11 and 12, respectively, and below the cross bar 11, above the table, the rods 10 carry a third cross bar 13, which slides freely on said rods. This cross bar 13 has stops 14, extending upwardly through holes in the cross bar 11, and arranged to limit the upward movement of the cross bar 13 by contacting with the top cross head 6. Each cross bar 13 may be provided with two or more of these stops, which may be adjustably connected thereto, as shown in the central bottle-filling device. In the form shown, the central bottle-filling device has two of these stops on its cross bar 13, while the other bars 13 each have one stop 14, and also another stop collar 13^a, extending outwardly from the cross bar and engaging a stop collar 14^a on the side support 5.

The numeral 15 designates a carrier which is loosely mounted on the rods 10, and to which is connected a filler head 16^a, a syrup pump 16, and a valve 17, for controlling the admission of aerated water into the chamber of the filling head.

18 designates coiled springs which are seated around the rods 10, between the carrier 15 and the cross bars 13. These springs seat within hollow sleeves 15^a surrounding the rods 10, above the guide lugs of the carrier 15.

15^a designates collars secured to the rods 10, below the carriers 15, for the purpose of raising the carriers in the manner herein-after described.

15^b designates a guard or shield which is connected to a projection 15^b on one of the collars 15^a. This shield is designed to act as a guard to stop any fragments of glass, in case of the breakage of a bottle during filling. Only one of these shields is shown in the drawings, but it will be understood that a similar shield may be provided for each set of bottling mechanisms.

The valve 17 has a valve stem 19, extend-

ing upwardly therefrom in the line of movement of a lug 11^a on the cross bar 11, said bar being arranged to move downwardly to cause the lug 11^a to engage 5 said stem and open the valve during the filling operation in the manner hereinafter described. The syrup pump 16 is provided with an upwardly extending stem 20 which is connected to the cross bar 11 and is arranged to be moved by said bar when the latter is moved relatively to the carrier 15.

The numeral 22 designates an inlet leading from a source of aerated water supply to one side of the valve 17, and 23 a connection leading from the other side of this 15 valve to the filling head 16^a.

24 designates the inlet from a syrup reservoir to the syrup pump 16. This syrup pump also has an outlet leading into the 20 connection 23.

I will now describe the air chamber shown in Figs. 4 to 6. During the filling operation, the air expelled from the bottle being filled results in a pressure being built 25 up within the chamber, but when this pressure becomes equal to the pressure of the aerated water supply, the flow of aerated water into the chamber will be stopped.

25 is a cylinder which is secured to and 30 extends upwardly from a boss or projection of the filling head 16^a.

26 is a passage leading from the filling head 16^a and communicating with the interior of the cylinder 25.

35 27 is a piston within this cylinder, said piston being connected to the lower end portion of a threaded rod 28, by means of a sleeve 29, and headed pin 30. This connection is of a character to permit the rod 40 28 to be freely rotated with relation to the piston. The rod extends upwardly through one of the tapped openings in the boss 7 of the cross bar 6, and is provided at its upper end with a hand wheel 31, by means of 45 which it may be turned to raise and lower the piston 27.

32 is a second cylinder which surrounds the cylinder 25 and which has a head 33.

34 is a tubular piston rod surrounding 50 the cylinder 25 and extending through the cylinder head 33; and 35 is a piston at the lower end portion of the tubular piston 34, the piston 35 having suitable packing forming an air-tight joint between it and the wall of the cylinder 32. The upper end of the tubular piston 34 is provided with a suitable packing to prevent leakage between it and the cylinder 25, and the joint between the cylinder 32 and the filler head 60 is also suitably packed. The cylinder 25 has ports 36 at its lower end which form a means of communication between the two cylinders 25 and 32, when the piston 35 is elevated above these ports. The piston rod 65 34 has projections 37, which are arranged to

register with recesses 38 in the cylinder head 33 when the piston 35 is moved down to the position in which it is shown in Figs. 4 and 5. After the piston 35 has been thus moved down, it is rotated from the position shown in Fig. 4 to that shown in Fig. 5, in order to lock it and its rod in their lowermost positions. Any number of these projections 37 may be provided, so that the piston 35 can be locked at any desired point intermediate 75 of the two positions shown, respectively, in Figs. 4 and 6.

If the machine is to be used for relatively small bottles, the piston 35 is moved to the position shown in Fig. 4, and locked in the 80 manner just described. The piston 27 is then raised or lowered relative to the size of the air chamber, so that the pressure built up within this chamber will equalize that in the aerated water supply pipe and stop 85 the flow when the predetermined quantity of liquid has been charged into the bottle. To fill larger sized bottles, the piston 35 is raised, and if necessary, the piston 27 can then be moved to obtain a more accurate adjustment of the air chamber.

In Figs. 1 and 2, I have shown the air chamber formed by a single cylinder 25^a, which is similar to the cylinder 25, except that its lower end is not provided with the 90 ports 36. One or more cylinders may be used for the equalizing chamber, the number and size of the cylinders being governed by the requirements of the particular machine.

The numeral 40 designates a power shaft journalled in the base standards 22, and having a driving pulley 41, or any other suitable driving connection.

42 is a rod which connects the standards 2, 2, and extends across the front of the machine. The shaft 40 carries the operating cams 43 and 44 for each bottle-filling mechanism. The cam 43 contacts with a roller 48, pivotally mounted in the lever 47, loosely 105 pivoted to the rod 42; while the cam 44 contacts with and actuates roller 45, which is journaled on the depending projection 46 of the cross head 12. Springs 49 connect the levers 47 with the cross bar 12 and act 110 to move the cross bar and the elements connected thereto downwardly when the lever is actuated by the cam. These springs also compensate for varying heights of bottles and give an automatic adjustment therefor. The springs are connected at their ends to 115 stems or hook bolts secured by nuts. The cams for the different filling mechanisms are set out of time with each other and are arranged to move the filling mechanisms with 120 relation to the bottle supports in the continuous rotation of the power shaft. It will therefore be seen that each set of bottling mechanisms comprises means for supporting the bottle, this being the table 3; means 125 130

for bringing the filling mechanism and the supporting means into filling relation; a source of still liquid supply; a source of charged liquid supply; and means controlled by the presence of a bottle on the bottle support for controlling the discharge of liquid from these two sources, a quantity of still liquid being first discharged, after which the valve controlling the supply of charged liquid is opened to admit a supply of the latter to the filling head.

The operation of the machine is as follows: Assuming the parts to be in their elevated positions, in which the roller 45 is engaged by the point 44^b of the cam 44, and the roller 48 is bearing against the flat portion 43^b of the cam 43, the bottle to be filled is placed on the table 3 below the filling head 16^a. As the shaft 40 is rotated, the cam 44 will move from under the roller 45 and permit the cross bars and the rods 10, together with the various elements mounted thereon, to move downward by gravity until the neck of the bottle is engaged by the mouth of the filling head, which will arrest the movement of the carrier 15. The further rotation of the shaft 40 will actuate the lever 47 through the medium of the cam 43 and move the rods 10 downward to their lowermost position, which position will be reached when the roller 48 is engaged by the concentric portion 43^c of the cam 43. During this downward movement of the rods 10, the neck of the bottle engaging the mouth of the filler head will be pressed thereon with sufficient pressure to form an air-tight joint. When the carrier 15 is stopped from further downward movement, the further movement of the rods 10 will move the cross bars 11 and 13, thereby compressing the springs 18 (which are seated in counter-bored portions of the loose sleeves 15^a on the carrier 15) sufficiently to thereby stop the rods 10 and cross bars 11 and 13 from further movement. The further movement of the lever 47 through the medium of the cam 43, after the rods 10 have been stopped from further movement by the engagement of the cross bar 13 and the guide lugs on the carrier, will be taken up by extending the springs 49. During the downward movement of the cross-bars 11 and 13, relative to the carrier 15, the syrup pump will first be actuated by its connection with the bar 11 to inject the syrup into the bottle being filled, and the lug 11^a will then strike the valve stem 19 and open the valve 17, to permit the aerated water to flow into the bottle, which will take place while the concentric portion 43^c of the cam 43 is passing over the roller 48. As soon as this portion of the cam passes off the roller 48, and the tension of the springs 49 has been relieved, the springs 18, through the cross-bars 11 and 13, will raise the rods 10, which will, in turn,

through the engagement of the collars 15^a with the carriers 15, raise said carriers and the filling head to the position in which the parts are shown in the middle filling mechanism of Fig. 1. The roller 45 will then be engaged by the cam 44 and raise the rods, together with all of the elements mounted thereon, through the medium of the collars 15^a, until the movement of the cross bar 13 is arrested by the stops 14. The further upward movement of the carrier 15 will compress the springs 18, and move the carrier and filling nozzle relative to the cross bar 13, to permit the removal of the bottle from the filling head. If either of the filling devices should be moved downward, when there is no bottle below the filling head, all of the elements connected to the rods 10 would move together without actuating the syrup pump or opening the valve 17. It will therefore be noted that the bars 11 form normally inoperative actuators for controlling the admission of liquid, these being rendered operative by the prevention of the downward movement of the bottle-filling head when the bottle is present. In other words, when the bottle is present in one of the mechanisms, it prevents downward movement of the bottle-filling head, and thereby holds the valve stem 19 in a position where it will be actuated by the lug 11^a. In such case, the bottle also causes the necessary relative movement to take place between the syrup pump attached to the filler head and the bar 11 to effect the operation of the pump.

By reference to Figs. 1, 7, 7^a and 7^b, it will be seen that the three machines will be operated successively. Figs. 7, 7^a and 7^b show the cams 43 and 44 for actuating the three machines and also show the cams in their relative positions with relation to each other. Each set of cams is set 120° from the set of cams adjacent thereto.

The advantages of my invention result from the provision of an automatic machine of a simple and improved type for filling bottles. By means of this machine, bottles may be filled at a high speed and with accuracy and precision. The filling operation is dependent upon the presence of a bottle on its support. The machine is capable of filling bottles of various sizes and capacities. By means of the closed pressure chambers in the filling heads, the amount of liquid going into the bottles can be controlled.

In connection with the machine, I will, of course, use any suitable form of closure-applying mechanism, such, for example, as that of my Patent No. 643,915, dated February 20, 1900.

I claim:

1. A bottling machine comprising a plurality of sets of bottling mechanisms fixed against lateral movement, each set includ-

- ing means for supporting the bottle and means for bringing the filling mechanism and bottle support into filling relation, a liquid-supply device, a normally inoperative actuator for the liquid-supply device, each bottling mechanism having a bottle-controlled means for rendering the said actuator of its own set effective independently of the other set or sets, and means for operating 10 the sets out of time, substantially as described.
2. In a bottling machine, the combination with a plurality of sets of bottling mechanisms fixed against lateral movement, each 15 set including a bottle support and means for bringing the filling mechanism and bottle support into filling relation, of a plurality of sources of liquid supply for different liquids, including connections controlled by 20 the bottle in each set, whereby each bottle may be filled from said sources, and means for operating said sets out of time, substantially as described.
3. In a bottling machine, the combination 25 with a plurality of sets of bottling mechanisms, each set including a bottle support, a filling mechanism, and a plurality of sources of liquid supply for different liquids, of a continuously operated cam shaft com- 30 mon to all the sets, valves for the sources of liquid supply, connections actuated by the cams on said shaft for bringing the filling mechanisms and the bottle support into and out of filling relation, and operating said 35 valves, and means whereby the valves are inoperative except when a bottle is present on said support, said cams being differently set to operate the different sets out of time, substantially as described.
4. In a bottling machine, the combination 40 with a plurality of sets of bottling mechanisms fixed against lateral movement, each set including means for supporting a bottle, a filling mechanism, and a plurality of 45 sources of liquid supply for different liquids, of a continuously rotating cam shaft located below the bottle supports, valves for said sources of liquid supply, valve-actuating connections operated by the cams on the cam 50 shaft, and means whereby said connections are inoperative except when a bottle is present on the support, substantially as described.
5. A bottling machine, comprising a plurality 55 of sets of bottling mechanisms fixed against lateral movement, each set including means for supporting the bottle, a filling mechanism, a plurality of sources of liquid supply for different liquids, and valves for 60 controlling said sources of supply, a continuously operating cam shaft common to all the sets of bottling mechanisms, separate connections actuated by said cam shaft for controlling the valves of each filling mechanism, and means whereby said connections 65 are inoperative except when a bottle is present on its support, substantially as described.
6. In a bottling machine, the combination with a plurality of sets of bottling mechanisms fixed against lateral movement, each 70 set including a bottle support, a filling mechanism, and a plurality of sources of liquid supply for different liquids for each filling mechanism, of a continuously operating cam shaft 75 located below the bottle support, cams on said shaft, levers operated by said cams, connections actuated by said levers for controlling said valves, means whereby said connections are inoperative except when a bottle is present on the support, and connections actuated by the cams on said shaft for operating the different sets out of time, substantially as described.
7. In a bottling machine, the combination 80 with a plurality of sets of bottling mechanisms, each set including a fixed bottle support and a filling head movable toward and away from said support, a continuously operating cam shaft common to all the sets, 85 cross-head members for moving the filling heads toward and away from the bottle support, and actuating connections between the cam shaft and said cross-heads, said connections including springs, substantially as described.
8. In a bottling machine, the combination 90 with a plurality of sets of bottling mechanisms, each set including a fixed bottle support and a filling head movable toward and away from said support, cross-head members for moving said filling heads, a cam shaft common to all the sets, cams on said shaft, said cams being set out of time with 95 each other, and connections actuated by the cams for actuating the cross-head members, substantially as described.
9. In a bottling machine, the combination 100 with a plurality of sets of bottling mechanisms, each set including a fixed bottle support and a filling head movable toward and away from said support, cross head members for moving said filling heads, a cam shaft common to all the sets, cams on said shaft, said cams being set out of time with each 105 other, and connections actuated by the cams for actuating the cross-head members, together with a plurality of sources of liquid supply for each filling mechanism, and means whereby said sources of liquid supply 110 are also operated by said cam shaft, substantially as described.
10. In a bottling machine, the combination 115 of means for supporting a plurality of bottles, a plurality of filling heads movable toward and away from the bottle-supporting means, a plurality of sources of liquid supply for each filling head, a cam shaft common to all the filling heads, connections operated by the cam shaft for actuating said 120 125 130

heads, said connections operating out of time with each other, and means also operated by the cam shaft for controlling the sources of liquid supply and inoperative except when a bottle is present on the supporting means, substantially as described.

11. A bottling machine, comprising a plurality of sets of bottling mechanisms, each set including a filling head, a bottle support, an automatic filling valve, a chamber communicating with the filling head and proportioned to the capacity of the bottle to receive gaseous pressure continuously from said filling head and the bottle during continuous entrance of the gas-charged liquid thereto, a continuously operating cam shaft, and connections operated by said shaft for bringing the filling heads and bottle support into filling relation, said shaft having its cams set at an angle to each other, whereby the sets of bottling mechanisms are operated out of time, substantially as described.

12. A bottling machine, comprising a plurality of sets of bottling mechanisms, each set including a filling head, a bottle support, an automatic filling valve, and a chamber communicating with the filling head and proportioned to the capacity of the bottle to receive gaseous pressure continuously from said filling head and the bottle during the continuous entrance of the gas-charged liquid thereto, a continuously operating cam shaft, and connections operated by said shaft for bringing the filling heads and bottle support into filling relation, said shaft having its cams set at an angle to each other, whereby the sets of bottling mechanisms are operated out of time, together with means whereby the capacity of each of said chambers may be separately adjusted, substantially as described.

13. A bottling machine, comprising a plurality of sets of bottling mechanisms, each set including a filling head, a bottle support, an automatic filling valve, and a chamber communicating with the filling head and proportioned to the capacity of the bottle to receive gaseous pressure continuously from said filling head and the bottle during the continuous entrance of the gas-charged liquid thereto, a continuously operating cam shaft, and connections operated by said shaft for bringing the filling heads and bottle support into filling relation, said shaft having its cams set at an angle to each other, whereby the sets of bottling mechanisms are operated out of time, together with means controlled in part by the cam shaft and in part by the presence of a bottle on the support for actuating the automatic filling valve, substantially as described.

14. A bottling machine, comprising a plurality of sets of bottling mechanisms, each set including a filling head, a bottle support, a plurality of sources of liquid supply, and

a chamber communicating with the filling head and proportioned to the capacity of the bottle to receive gaseous pressure continuously from said filling head and the bottle during the continuous entrance of the gas-charged liquid thereto, a continuously operating cam shaft below the bottle support, and having thereon a plurality of cams set in different angular positions, connections operated by said cams for bringing the filling heads and bottle support into filling relation to each other, and means also operated by the cams for controlling said sources of liquid supply, substantially as described.

15. A bottling machine, comprising a plurality of sets of bottling mechanisms, each set including a filling head, a bottle support, a plurality of sources of liquid supply, valves for controlling said sources, and a chamber communicating with the filling head and proportioned to the capacity of the bottle to receive gaseous pressure therefrom, a continuously operating cam shaft having a plurality of cams thereon set at different angles, levers actuated by said cams for bringing the filling heads and bottle support into filling relation, connections operated by said cams for actuating said valves, and means whereby the valves of any filling mechanism are not actuated unless a bottle is present on its support, substantially as described.

16. A bottling machine, comprising a bottle support, a filling head, a plurality of sources of liquid supply for said filling head, valves for controlling said sources of supply, a continuously operating power shaft, cams on said shaft, and connections operated by said cams for bringing the filling head and bottle support into and out of bottle filling relation, together with means controlled in part by said cams and in part by the presence of a bottle on said support for actuating said valves, substantially as described.

17. A bottling machine, comprising a bottle support, a filling head, a plurality of sources of liquid supply for said filling head, valves for controlling said sources of supply, a continuously operating power shaft, cams on said shaft, and connections operated by said cams for bringing the filling head and bottle support into and out of bottle filling relation, together with means controlled in part by said cams and in part by the presence of a bottle on said support for actuating said valves, said connections including spring members, substantially as described.

18. A bottling machine, comprising a bottle support, a filling head movable toward and away from said support, a cross-head member carried on the filling head, a continuously operating power shaft having a cam thereon, connections between said cam and the cross-head member, a plurality of

- sources of liquid supply for said head, and means controlled by the contact of the head with a bottle on said support for controlling the operation of said valves, substantially as described. 5
19. A bottling machine, comprising a bottle support, a filling head, a syrup pump for supplying syrup to said head, a source of water supply having a valve provided with 10 a projecting stem, a continuously operating power shaft, a normally inoperative vertically movable member for operating said pump and the stem of the water valve, and connections for actuating said member from 15 said shaft, said connections including spring means controlled by the presence of a bottle on the support, substantially as described.
20. A bottling machine, comprising a bottle support, a filling head, a syrup pump for supplying syrup to said head, a source of water supply for the filling head having a valve, a continuously operating power shaft, and a member operated by said shaft for operating said pump and the stem of the 25 water valve, said connection being normally inoperative to move the valve, the operative engagement of said member with the syrup
- pump and valve being controlled by the presence of a bottle on the support, substantially as described. 30
21. In a bottling machine, the combination with a plurality of sets of bottling mechanisms, each set including a bottle support, a filling mechanism and a plurality of sources of liquid supply for different liquids, of a continuously operated cam shaft common to all the sets, valves for the sources of liquid supply, connections actuated by the cams on said shaft for bringing the filling mechanisms and the bottle support into and out of filling relation, said connections including a normally inoperative valve-actuating device and also spring means controlled by the presence of a bottle on the support to render said valve-operating device operative, 35 40 45 substantially as described.

In testimony whereof, I have hereunto signed my name in the presence of two subscribing witnesses.

PATRICK W. SHIELDS.

In the presence of—
